UNITED STATES PATENT OFFICE

HENRY M. NICHOLLS, OF CHICAGO, ILLINOIS, ASSIGNOR TO AMERICAN CAN COMPANY,
OF NEW YORK, N. Y., A CORPORATION OF NEW JERSEY

CONTAINER

Application filed May 9, 1927. Serial No. 189,811.

This invention relates in general to containers and has for a principal object the provision of a container having a bail attachable to the container in two positions in one of which the bail has normal free swinging connection with the container, and in the other of which the bail is locked in engagement with the external surface of the container lying wholly within the confines of the upper and lower container seams in order to provide a container adapted for rolling through the ordinary can handling machinery without interference from the bail and which may be rolled on its end closure seams.

A further important object of the invention is the provision of a bail for containers adapted for attachment upon the container by merely snapping a slotted portion of the bail upon lugs secured to the container and which may be locked in engagement upon the surface of the container when not in use, as during packing and shipment, and which may be shifted upon the container lugs to unlock the bail for normal use.

Still another important object of the invention is the provision of an easily attachable bail for containers which is simple and strong and which cannot readily become detached from attached position on the container.

Numerous other objects and advantages of the invention will be apparent as it is better understood from the following description, which, taken in connection with the accompanying drawings, discloses a preferred embodiment thereof.

Referring to the drawings:

Fig. 1 is an elevational view of a container embodying my invention;

Fig. 2 is a similar view of the same container illustrating a final step of the bail unlocking process;

Fig. 3 is a similar view partly showing the bail temporarily locked against the side walls of the container, and illustrating the possi-

bility of rolling the container upon its end closure seams without interference from the bail;

Fig. 4 is a section taken substantially on line 4—4 in Fig. 3; and

Fig. 5 is an enlarged detail view illustrating the novel method provided for connecting the bail to the container.

To illustrate my invention I have shown on the drawings a container of the usual type having a body 11, seamed end closures 12 and 13, and a bail 14. The body 11 may have any convenient shape, the container herein disclosed being cylindrical and is provided with bail lugs 15 oppositely secured to the side walls of the container adjacent the top. The end closures are of any suitable type and are secured to the container body by means of a double lap seam 16. The container body is thus formed with a portion 11 of smaller diameter and a portion 16 of larger diameter. The bail lugs 15 are formed of sheet metal formed to provide a flange 17, a neck 18 of reduced diameter and a base portion 19. The body 11 is oppositely recessed adjacent the top edge to provide sockets 21 adapted to engage the base portion 19 of the lugs, and the lugs are secured to the body 11 by spot-welding, soldering, or in any suitable manner.

The bail 14 is formed of a sheet metal strip having curled edges 22 to provide reinforcement. The bail has a shape adapted to embrace the external surface of the body 11 when engaged therewith and is provided with a slot in at least one end and preferably in both ends. This slot has a particular shape and is arranged to provide adjustable engagement of the bail and its supporting lugs. The slot is adapted to provide engagement between the bail and the lugs at a plurality of remote points in the bail and comprises a straight sided aperture 23 the lower end 25 of which is rounded and arranged to engage the neck portion 18 of the lug 15 when the bail has normal engagement as illustrated in Fig. 90

1 of the drawings. The upper end of the slot 23 opens into two upper slot portions 24. These portions open into each other and into the lower slot portion and are rounded to engage the neck 18 of the lug. The slot has a substantially trifolium outline. The opening between the slot portions 24 and 23 is reduced to provide a locking shoulder 26, the opening being sufficiently large to allow the lug to be snapped from engagement in the main slot portion 23 into engagement in either of the side slots 24. The slot portions 24 provide means for changing the center of suspension of the bail upon the bail lugs so that the bail may be collapsed from normal position into engagement upon the container walls as shown in Fig. 3 of the drawings by rotating the bail in either direction through 90° from the normal position shown in Fig. 1, and pushing it into engagement with the side walls of the can body, the lug sliding longitudinally through the slot portion 23 until opposite the slot portions 24 whence it is forcibly engaged in the lower of the two portions past the locking shoulder 26. The slot portions 24 are so positioned in the bail that when the lugs are engaged therein, the bail is held securely engaged against the outer side of the container body the bail having an upwardly disposed side edge parallel with and adjacent to the upper container seam 16. The slots 24 may be arranged in the slot 23 to permit the bail to be locked with its upwardly disposed edge as close to the end seam as desired, or the bail edge and end seam may be arranged to engage to provide firmer bail engagement. The shape of the slots allows the bail to be readily assembled upon the lugs by sliding the edge of the lug flange 17 through the slots 24 and over the shoulder portions 26 whence the neck of the lug is forced into the slot 23 until the lug flange 17 snaps into engaged position over the upper edge 27 of the slot as shown in Fig. 5 of the drawings. The bail may be locked in engaged position upon either side of the container since the lug may be engaged with either of slot portions 24. In collapsed position the bail is secured against the container walls and it is evident that the container may be rolled in conveying or can handling machinery and that it may be packed without interference from the bail and in fact as if there was no bail. The efficiency of the bail, however, is not impaired by the novel arrangement of the parts.

It is though that the invention and many of its attendant advantages will be understood from the foregoing description, and it will be apparent that various changes may be made in the form of the container and in the construction and arrangement of the parts without departing from the spirit and scope of the invention or sacrificing all of its material advantages, the form hereinbefore de-

scribed being merely a preferred embodiment thereof.

I claim:

1. A bail for containers consisting of a sheet metal strip having longitudinal slots 23 formed in its end portions; said slots having lateral extensions of a width to receive the shanks of the bail pivot lugs, said extensions locking the bail relative to the lug, and holding the bail against outward movement when it is nested against the side of the container to which said bail is applied, the sheet metal of the bail being yieldable to permit the ends of the bail to slide edgewise into engagement under the heads of said lugs. 70

75

2. The combination of a container having a laterally and outwardly projecting part, and a sheet metal bail having longitudinal slots 23 formed in its end portions, said slots having lateral extensions of a width to receive the shanks of the bail pivot lugs, said extensions locking the bail relative to the lug, and holding the bail against outward movement when it is nested against the side of the container and against said outwardly extending part, the sheet metal shoulder portions at the points where said slots and lateral extensions intersect being yieldable to permit the ends of the bail to slide edgewise into engagement under the heads of said lugs. 80

85

90

3. A bail for containers consisting of sheet metal formed with longitudinal slots at its ends and with a lateral extension of said slot forming a shoulder, in combination with pivot lugs for the ends of said bail having heads over which the ends of the bail may be slipped into pivotal and locked position by the yielding of the sheet metal of the bail at said lateral extension, said shoulder forming a stop to hold the bail nested against the side of the container. 100

95

4. The combination of a container body having pivot lugs, and a bail having slots engaging said lugs and adapted to suspend the can, the bail being slidable and collapsible inward on said lugs against the outer side of the container body, and releasable means fixedly associated with the ends of the bail and functionally related to the lugs, for locking the bail, when in the latter position, and keeping it against the outer side of the container. 110

105

5. The combination of a container body having pivot lugs, and a bail having slots engaging said lugs and adapted to suspend the can, the bail being slidable and collapsible inward on said lugs against the outer side of the container body, said slots having offset portions adapted to receive the lugs for locking the bail, when in the latter position, and keeping it against the outer side of the container. 120

115

6. The combination of a container body formed with a portion of larger diameter and a portion of smaller diameter, pivot lugs on 130

125

5 said portion of small diameter, and a bail having slots engaging said lugs and adapted to suspend the container, the bail being slideable and collapsible inward on said lugs against the outer side of said container portion of smaller diameter, whereby said container portion of larger diameter projects outward substantially as far as the collapsed bail, and releasable means fixedly associated with the
10 ends of the bail and functionally related to the lugs, for locking the bail when in the latter position and keeping it within the line of the circumference of said portion of larger diameter.
